UNITED STATES PATENT OFFICE

2,377,162

PORTABLE TELEPHONE

Jack L. Long, United States Army

Application February 18, 1944, Serial No. 522,994

6 Claims. (Cl. 179—29)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a portable telephone in which all the apparatus which can be connected to lines for receiving at and transmitting from one place are mounted on a casing which can be carried about and held in one hand of an operator during use.

Objects of this invention are therefore; first, to provide a handy, portable telephone; second, to provide, in a telephone system, a ringing circuit in which the signal is energized from a local battery in the talking circuit; and third, to provide in such a telephone system a sensitive relay which controls the signal device.

These objects may be obtained by the mechanism disclosed in the drawing annexed hereto and described as follows.

In the drawing:

Fig. 1 is a circuit diagram of the device.

Fig. 2 is a perspective view of the device.

One embodiment of the invention shown in Fig. 2 comprises a casing 1 having a detachable cover 2 and is conveniently made of sheet metal and is of such a size as to be conveniently grasped in one hand of the user and held in position so that the receiver 3 is adjacent his ear while the microphone or transmitter 4 is juxtaposed to his mouth. Handle 5 operates ringing switch 6—7—8 while handle 9 operates talking switch 10—11—12—13. Pigtails 15 and 16 represent the line connections.

Referring now to Fig. 1, it is to be understood that all the elements are enclosed within casing 1 and cover 2 except handles 5 and 9, pigtails 15 and 16, receiver 3, and transmitter 4, all of which are carried by casing 1 or cover 2. Connected between line 15 and switch point 6 is battery 17. Relay coil 18 is connected between switch points 8 and 13. Signal 19 and relay contacts 20 and 21 are connected in series across local battery 22. The microphone or talking circuit includes movable switch member 11, stationary switch contact 12, battery 22, transmitter 4, induction coil 23 and switch point 10. Line wire 16 is connected in series with receiver 3, induction coil 24, switch point 10, and line wire 15.

The operation of my device as a receiving station will be readily understood from a consideration of Fig. 1 bearing in mind that a sending station identical with the circuit shown in Fig. 1 is connected to lines 15 and 16. At the sending station, handle 5 is operated to engage switch

contacts 6 and 7 and thereby connect battery 17 across line wires 15 and 16. At the receiving station shown in Fig. 1, electricity passes from line wire 16, switch contacts 7, 8, relay coil 18, and switch contacts 13, 11 to line 15. This energizes relay coil 18 and solicits movable contact 20 into engagement with stationary contact 21. Closure of contacts 20 and 21 completes a circuit through electric bell 19 and battery 22. 10 When the attention of the user is arrested by a signal from bell 19, he operates handle 9 to open switch contacts 11, 13 and close switch contacts 11, 10 and 12. Opening contacts 13, 11 de-energizes coil 18 and, therefore, signal 19, while closing contacts 11, 10, 12, throws receiver 3 and transmitter 4 into the talking circuit and permits talking over the telephone. Upon the end of the conversation, handle 9 should be operated to open contacts 11, 10, 12 and close contacts 11, 15. 20 The telephone is then in condition to receive another call or to call another station by moving handle 5 so as to engage contacts 6, 7.

One advantage of this new telephone arrangement is that the ringing current for electric bell 19 need not be transmitted over the line wires 15 and 16. Instead of transmitting the relatively large amount of power necessary to ring bell 19 over the line 15, 16 a small current at relatively high voltage (say 22 volts for example) 25 from battery 17 at the sending station is transmitted to the sensitive relay 18 at the receiving station. At the receiving station, the sensitive relay closes the bell circuit through the relatively low voltage (say six volts for example) 30 from battery 22 which rings the bell 19. It is understood that battery 17 is the equivalent of and may be replaced by a small hand generator.

I claim:

1. A ringing circuit for a telephone system 35 having a line circuit and having a local battery in the microphone circuit comprising a signaling device and a normally open electric switch connected in series across said local battery, and a normally closed ringing switch and an electrically-operated means for closing said normally open electric switch and a normally closed talking switch connected in series across the line circuit whereby a flow of electricity through the line circuit energizes said electrically-operated 40 means and causes it to close said normally open electric switch and cause actuation of said signaling device.

2. A portable telephone handset adapted for connection to a temporary line or the like comprising a casing adapted to be grasped by the 45

hand and having the following elements mounted on it, a battery and a normally open ringing switch connected in series and adapted for connection across the line, a normally open microphone switch and a local battery and a transmitter and a receiver connected in series and forming a talking circuit adapted for connection across the line, a normally open local switch and a signaling device connected across said local battery, and a normally closed second talking switch and an electrically-operated means for closing said normally open local switch and a normally closed third talking switch connected in series and adapted for connection across the line.

3. In a telephone handset for connection to a line, a casing carrying a transmitter adjacent one end and a receiver adjacent the other end, a normally open talking switch and a local battery both in said casing and connected in series so as to be placed across the line, means for attracting the attention of a user and normally open relay contacts both in said casing and connected in series with said local battery, and a manually operable ringing switch and a coil operating said relay contacts both in said casing and connected in series with the line, said coil, when energized, serving to close said relay contacts and connect said means in circuit across said local battery, thereby causing said means to operate.

4. In a portable telephone sending and receiving unit for use with a line and including a sheet metal casing consisting of a cover and a housing, said housing being adapted to be grasped by the hand of the operator to support the entire casing thereby, a microphone and a receiver both mounted on said casing, said microphone and said receiver being so spaced that they may be located simultaneously in juxtaposition to the mouth and ear respectively of the operator when the operator supports the casing by hand, a local battery in said casing and connected in series with said transmitter, a signal relay in said casing and having contacts, signaling means in said casing and connected in series with said contacts and said local battery, and a manually operable switch in said casing connected in series across the line so that said relay when energized closes said contacts and causes said signal to be operated.

5. Portable telephone equipment for use with a line and including transmitting apparatus and

receiving apparatus, a casing serving as a mounting for said apparatuses and affording a grip for one hand of an operator, a talk control switch mounted upon said casing and electrically connected to a local battery in said casing and to said apparatuses, whereby when said switch is closed said apparatuses are connected to the line, said switch including an operating member extending outside of said casing, and a signal-receiving device mounted on said casing and electrically connected to the line, said device including a switch operating handle projecting from said casing, a switch in said casing and arranged for manual operation by said handle, a relay-coil in said casing and connected under the control of said switch, relay contacts under the control of said relay coil, and a signal in said casing and connected in series with said relay contacts across said local battery.

6. In a portable telephone system, a handset comprising a casing of such length and small size that it may be grasped by the hand and opposite ends thereof placed adjacent an ear and the mouth respectively of the operator, a two wire line entering the casing, a microphone adjacent one end of said casing and supported thereby, a receiver adjacent the other end of said casing and supported thereby; and the following parts all located in said casing; a local low voltage battery, a bell and normally open relay contacts in series with said battery, a relay having a coil for operating said contacts, a single pole double throw switch having first and second contacts which may be alternately energized by the pole of the switch, means connecting the pole of the switch to the first side of said line, means connecting the first contact to one side of said relay coil, a normally closed manually operable switch, means connecting the other side of said relay coil through said last-mentioned switch to the second side of said line, a relatively high voltage source, means connecting the second contact of said double throw switch through said high voltage source to the second side of said line, said receiver being connected in series with said line, a microphone transformer having a primary winding in series with said microphone and local low voltage battery and having a secondary winding, and a normally open switch connected in series with said microphone and the second side of said line.

JACK L. LONG.
